BED HEADBOARD

Richard G. Barr, Watchung, N.J., assignor to Thomasville Furniture Industries, Inc., Thomasville, N.C., a corporation of North Carolina

Filed Oct. 11, 1966, Ser. No. 4,239

Term of patent 14 years

(Cl. D5—4)

The back of the headboard is the same in appearance as the front thereof.

I claim:

The ornamental design for a bed headboard, as shown and described.
